CLAIM

The ornamental design for a camera head for a video recorder, as shown and described.

DESCRIPTION

FIG. 1 is a front elevational view of the camera head for video recorder showing our new design, the rear elevational view being a mirror image of the front elevational view, and the top and bottom plan views being identical to the front elevational view;

FIG. 2 is a right side elevational view thereof;

FIG. 3 is a left side elevational view thereof;

FIG. 4 is a perspective view taken from the front, top and left side of the camera head for a video recorder; and,

FIG. 5 is a perspective view taken from the front, top and left side of the camera head for a video recorder connected to a video recorder/player that is shown in broken lines for illustrative purposes only, forming no part of the claimed design.

It is understood that a camera head for a video recorder shown cut away in the center is to indicate that no particular length is claimed.
